UNITED STATES PATENT OFFICE

157,094

EMBROIDERED TEXTILE FABRIC OR SIMILAR ARTICLE

Clara R. Slepiski, Chicago, Ill., assignor to Fixler
Bros., Chicago, Ill., a copartnership

Application June 15, 1949, Serial No. 3,286

Term of patent 3½ years

(Cl. D92—26)

To all whom it may concern:

Be it known that I, Clara R. Slepiski, a citizen of the United States and a resident of the city of Chicago, in the county of Cook and State of Illinois, have invented a new, original, and ornamental Design for an Embroidered Textile Fabric or Similar Article, of which the following is a specification, reference being had to the accompanying drawing, forming a part thereof.

On the drawing, the figure is a plan view of the embroidered textile fabric or similar article, showing my new design.

The embroidered textile fabric is shown against a black background to bring out the details of the design.

I claim:

The ornamental design for an embroidered textile fabric or similar article, as shown and described.

CLARA R. SLEPSKI.
